ment being generally designated at 40 in FIG. 3. Here a resilient means in the form of an elongated spring member 41 is secured at its ends to the suspension slat 32 as indicated at 42. This spring member 41 is provided with a bracket 43 which carries a bale 44 which is adapted to be hooked over the hook member 20. This resilient means, including the spring member 41, is utilized for the purpose of tensioning the flexible screen 31 to provide an extremely flat surface. This resilient means is capable of applying a greater tensioning force to the screen 31 than can be applied by the spring actuated roller. In order to prevent the screen case from moving upwardly, under the tensioning afforded by the spring member 41, a handle member 45 may be utilized, and this handle member 45 may be of the type shown and described in my co-pending application Serial No. 418,946, filed March 26, 1954. This handle member 45 is illustrated in more detail in FIG. 4. Here the handle member 45 is slidably mounted on the upright post or tube 11 and is provided with a handle portion 46. Located within the handle member 45 is a double acting nipping lever 47, the end 48 of which extends out from the handle member 45 for manipulation purposes. The nipping lever 48 pivots about a shoulder 51 in the handle member and is provided at its inner end with a post 49 surrounded by a spring 50. The shoulder 51, post 49 and spring 50 operate in conjunction with the nipping lever 47 to prevent movement of the handle member 45 in either direction on the post 11, but when the nipping lever 47 is manipulated through its extension 48, the handle member 45 may be adjusted to any position along the post 11. Since the handle member 45 is locked against movement in the upward direction, it is therefore possible to apply tension to the flexible screen 31 afforded by the resilient means including the spring member 41.

Referring more particularly to FIGS. 5 to 7, a mechanism is provided for positively limiting the unrolling of the flexible screen 31 from its carrying roller, this mechanism affording two main functions, one function is to absolutely prevent tearing or separation of the screen from the roller and the other function is to co-operate with the tensioning means illustrated in FIG. 3 to provide for the tensioning of the flexible screen in picture exhibiting position, which is particularly useful in the exhibiting of three-dimensional pictures. In the arrangement of FIGS. 5 to 7, there is provided a post 55 having a flange 56 and a squared extension 57 which is secured against rotation to the end cap 35 of the screen case 30. A spacer member 58 having a squared hole, also receives the squared extension 57 of the post 55 and is secured to the end cap 35, as by welding or the like, to aid in supporting the post 55. The post 55 is rigidly secured to the spacer 58 and the end cap 35 by peening over the end of the squared extension 57 where it extends through a squared hole in the end cap 35, the peening being illustrated at 59.

Rotatably mounted on the post 55 is a bracket 61 which is secured by rivets 63 or the like to one end of a roller 62. In this way this end of the roller 62 is mounted for rotation on the post 55. The other end of the roller 62 may be mounted for rotation and may be provided with spring means for rotating the roller 62 in a rolling direction in the manner illustrated and described in my aforementioned co-pending application Serial No. 418,946, filed March 26, 1954. Preferably, the roller 62 is formed from an extruded tube having a shoulder 63 of a height substantially equal to the thickness of the flexible screen which is rolled on the roller. The end of the flexible screen 31 is butted against the shoulder 63 and is suitably secured in place on the roller 62 by a suitable adhesive or the like. Due to this shoulder 63 and the butting of the flexible screen thereagainst, a smooth surface is at all times presented to subsequent layers of the flexible screen as it is rolled on the roller and, according-

ly, any tendency to develop wrinkles or indentations in the screen is eliminated.

The roller 62 adjacent one-edge of the screen 31 and adjacent the shoulder 63 in the roller, is provided with an opening 64, one edge 65 of the opening acting as a stop edge and another edge 66 thereof operating as a camming edge. This opening 64 in the roller is normally covered by the screen 31 rolled upon the roller and it is exposed only when the screen 31 is unrolled to uncover the opening, i.e. to its last turn from the roller, as illustrated in FIG. 6. A mounting bracket 68 is secured to the inside of the screen case 30, as by welding or the like, in alignment with the opening 64 in the roller 62. This bracket 68 is provided with a pair of ears 69 for pivotally mounting a stop member 70 having arms 71. A pin 72 extends through the ears 69 on the mounting bracket 68 and the arms 71 on the stop member 70 for pivotal mounting purposes. A spring 73 arranged about the pin 72 and contacting at its ends the stop member 70 and the bracket 68, operates to resiliently urge the outer end of the stop member 70 toward the roller 62. The stop member 70 is provided at its outer end with a stop shoulder 74, which is adapted to engage the stop edge 65 of the opening 64 in the roller 62, and it is also provided with cam means 75 which is adapted to be engaged by the camming edge 66 of the opening 64 in the roller 62.

When the screen 31 is rolled upon the roller 62, the stop member 70 rides upon the screen rolled upon the roller, and, since the screen 31 covers the opening 64 in the roller 62, the stop member 70 is prevented from entering the opening 64. Thus, the roller 62 may be freely rotated without interference from the stop member 70 when the screen 31 is rolled upon the roller. This allows the flexible screen 31 to be freely unrolled from the roller 62 and withdrawn from the screen case 30. When, however, the screen 31 is unrolled from the roller 62, to the last turn, as illustrated in FIG. 6, the opening 64 in the roller 62 is uncovered and the free end of the stop member 70 is advanced by the spring 73 into the opening 64. When this occurs, the stop shoulder 74 on the stop member 70 engages the stop edge 65 of the opening 64 in the roller 62 and stops further rotation of the roller 62 in an unrolling direction. This, therefore, prevents complete unrolling of the screen from the roller and otherwise prevents tearing and separation of the screen from the roller. This positive stopping of the roller at this position also makes it possible to tension the flexible screen 31. Thus, when the flexible screen 31 is withdrawn to picture exhibiting position wherein the screen is unrolled from the roller to the last turn to uncover the opening, and the bale 44 is secured to the hook member 20, the hook member 20 and the handle member 45 may be adjustably moved apart with respect to each other, and due to the action of the spring member 41, as illustrated in FIG. 3, a large amount of tension is applied to the flexible screen 31 to maintain it in a flat condition which is admirably suited for the projection of three-dimensional pictures.

60 When it is desired to roll the screen upon the roller in the screen case, the extended screen is detached from the hook member 20 and the spring actuated roller 62 operates automatically to roll the screen thereon. As the roller 62 is thus rotated in the rolling direction for this purpose, the cam means 75 on the stop member 70 is engaged by the camming surface 66 of the opening 64 to raise the stop member 70 from the opening 64, so that free rolling of the screen on the roller is assured.

Referring now to FIGS. 8 to 10, another form of mechanism is illustrated for accomplishing the same results as are accomplished by the mechanism of FIGS. 5 to 7. Here, like reference characters have generally been utilized for like parts. The flexible screen 31 is secured to the roller 62 against the shoulder 63 in the manner described above. A stop member 80 is provided with a

mounting ear 81 which carries a pin 82 which, in turn, pivotally mounts the stop member 80 in a bearing member 83 secured to the end cap 35 of the screen case 30, the pin 82 and the stop member 80 being held in place by peening over the end of the pin 82. A spring 84 engaging the stop member 80 and the spacer 58, normally urges the stop member 80 toward the roller 62. The stop member 80 is provided with an ear 85 which is in alignment with the opening 64 in the roller 62, and this ear 85 is provided with a stop shoulder 86 for engaging the stop edging 65 of the opening 64 and a cam means 87 for engaging the camming edge 66 of the opening 64. The stop shoulder 85 and the cam means 87 of the stop member 80, operate in the same manner as described above in connection with the mechanism illustrated in FIGS. 5 to 7 and, therefore, a further description is not considered necessary. The ear 85 also preferably carries a wheel means 88 which rolls upon the screen 31 where it is rolled upon the roller 62, this wheel means 88 operating to prevent wear upon the screen during rolling and unrolling of the screen on the roller.

Another form of projection screen of this invention is generally designated at 90 in FIG. 11, this form of projection screen being of the wall mounted type wherein the flexible screen 31 is withdrawn downwardly from the screen case 92 by pulling on the slat 32. The screen case 92 may be suitably mounted on a wall or the like by a supporting member 91 and the screen case may be provided with suitable end caps 93. This form of the invention, in addition to providing a mechanism for preventing tearing or separation of the flexible screen from the roller, also includes provision for holding the screen in withdrawn position. The details of the mechanism of the projection screen 90 are illustrated in FIGS. 12 to 15.

Secured in the screen case 92 adjacent each end thereof are brackets 94 which are utilized for supporting the roller 95 within the screen case. At one end the roller 95 is provided with a bracket 96 which carries a pin 97 which is rotatably mounted in the adjacent bracket 94, this one end of the roller 95 thereby being supported for rotation within the screen case 92. Arranged at the other end of the screen case is a shaft 99 having a non-circular end 100 which is received in a non-circular opening in the other bracket 94. In this way the shaft 99 is secured against rotation with respect to the screen case 92. The shaft 99 adjacent the bracket 94 is provided with a collar 101 which, in turn, is provided with a latch shoulder 102. A bracket 104 having longitudinally extending ears 105 is secured by rivets 106 to the end of the roller 95. The bracket 104 is provided with a round hole for receiving the shaft 99 so that this end of the roller 95 is rotatably mounted on the shaft 99 and supported thereby. The bracket 104 is provided with a pair of ears 107 struck therefrom and one end of a coil spring 108 is secured to these ears. The other end of the coil spring 108 is secured to a bracket 109 which, in turn, is secured to the shaft 99. The inner end of the shaft 99 is rotatably mounted in a bracket 110 secured within the roller 95 so as to provide an inboard support for the inner end of the shaft 99. The spring 108 connected between the stationary shaft 99 and the bracket 104 secured to the roller 95 operates to rotate the roller 95 in a rolling direction.

A pawl 115 is pivotally mounted on the bracket 104 by means of a pivot pin 116. This pawl has a shoulder 117 which is adapted to engage the shoulder 102 on the collar 101 when the pawl swings inwardly toward the axis of rotation of the roller 95. When the roller 95 is stationary or moving slowly and the pawl is arranged above the collar 101, as illustrated in FIG. 14, the pawl 115 swings inwardly so that the shoulder 117 thereof engages the latch shoulder 102 on the collar 101. When this occurs, rotation of the collar 95 in a rolling direction by the spring 108 is prevented. When, however, the roller is rotated rapidly, the pawl 115 swings outwardly

by centrifugal force so that its shoulder 117 does not engage the shoulder 102 on the collar 101, and under these conditions of rapid rotation the roller is rotated by the spring 108 to roll the screen 31 thereon. By reason of the pawl 115 and the stationary collar 101, the screen 31 may be withdrawn downwardly from the screen case 92 and then latched in that position. When it is desired to retract the flexible screen 31 into the screen case 92, the screen 31 is given a tug and allowed to retract rapidly into the screen case 92.

The form of the invention illustrated in FIGS. 11 to 15 also includes the opening 64 in the roller 95 and the stop member 70 pivotally carried by the screen case 92, as described above in connection with the form of the invention illustrated in FIGS. 5 to 7 and like reference characters have been utilized for like parts. The stop member 70, which is in alignment with the opening 64 operates in conjunction with the opening 64 to prevent further rotation of the roller in the unrolling direction 20 when the screen is unrolled therefrom to uncover the opening, i.e. to the last turn to prevent further unrolling of the screen from the roller. When the screen is rolled upon the roller 95, the opening 64 in the roller is covered by the screen rolled thereon, and thus the roller 95 may 25 be freely rotated in the unrolling direction against the action of the spring 108 to allow downward withdrawal of the flexible screen 31 from the screen case 92. When the flexible screen 31 is unrolled to the last turn, the opening 64 in the roller is uncovered and the stop member 70 is advanced into the opening by the spring 73. When this occurs, further rotation of the roller 95 in the unrolling direction is stopped to positively prevent tearing or separation of the flexible screen 31 from the roller 95. The roller 95 is then allowed to rotate slowly 30 in a rolling direction until the shoulder 117 on the pawl 115 engages the latch shoulder 102 on the collar 101, whereupon rolling rotation of the roller 95 is stopped and the screen is maintained in picture exhibiting position. It is noted that at least substantially 180 degrees 35 of rotation of the roller is provided between the point where the stop shoulder 74 on the stop member 70 engages the stop edge 65 of the opening 64, and the point where the latch shoulder 117 of the pawl 115 engages the latch shoulder 102 on the collar 101. This is to 40 allow sufficient rotation of the roller in the unrolling direction to permit rapid rolling of the roller in the rolling direction so that, when it is desired to retract the screen into the screen case, the shoulder 117 of the pawl 115 will not engage the latch shoulder 102 on the collar 101. This relationship of these parts assures correlated 45 operations of the stop mechanisms which limit unrolling of the screen and which permit controlled rolling of the screen on the roller. By mounting the pawl 115 on the bracket 104 which bracket is fixed with respect to the opening 64 in the roller 95, these angular relations may 50 be positively determined and maintained.

In all forms of the invention herein disclosed, there are provided cooperating members carried by the screen case and roller, which members are controlled with respect to each other by the screen on the roller, to allow unrolling of the screen from the roller to picture exhibiting position until the screen is unrolled to uncover the opening, i.e. to the last turn and then to stop further unrolling of the screen from the roller whereby tearing and separation of the screen from the roller are entirely eliminated. In the form of the invention contemplated in FIG. 3, this mechanism for limiting the unrolling of the screen from the roller also cooperates with the tensioning means associated with the suspension slat for providing a simple and effective arrangement for tensioning the screen so as to make it particularly adaptable for use in exhibiting three-dimensional pictures. In the form of the invention contemplated in FIGS. 11 to 15, this mechanism for limiting the unrolling of the screen from the roller operates in conjunction with other cooperat-

ing members carried by the screen case and the roller, which prevent slow rotation of the roller in the rolling direction but permit rapid rotation of the roller in the rolling direction for the purpose of maintaining the screen in picture exhibiting position, this being particularly desirable in a projection screen of the wall mounted type.

While for purposes of illustration, several forms of this invention have been disclosed, other forms thereof may become apparent to those skilled in the art upon reference to this disclosure and, therefore, this invention is to be limited only by the scope of the appended claims.

I claim as my invention:

1. In a projection screen for use in exhibiting pictures and having a screen case, a spring actuated roller rotatably mounted in the screen case, a flexible screen secured at one end to the roller and being automatically rolled thereon and having a slat at its other end for unrolling the screen from the roller to picture exhibiting position, the improvement comprising, said roller having an opening therein which is normally covered by the screen rolled thereon and which is exposed only when the screen is unrolled to its last turn, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to the last turn, said stop member having a stop shoulder engaging one edge of the opening in the roller when the stop member is advanced into the opening to stop further rotation of the roller in the unrolling direction and prevent further unrolling of the screen from the roller, and having cam means engaging another edge of the opening in the roller for retracting the stop member from the opening when the roller is rotated in the rolling direction to roll the screen upon the roller.

2. In a projection screen for use in exhibiting pictures and having a screen case, a spring actuated roller rotatably mounted in the screen case, a flexible screen secured at one end to the roller and being automatically rolled thereon and having a slat at its other end for unrolling the screen from the roller to picture exhibiting position, the improvement comprising, said roller having an opening therein which is normally covered by the screen rolled thereon and which is exposed only when the screen is unrolled to uncover the opening, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to uncover the opening, said stop member having a stop shoulder engaging one edge of the opening in the roller when the stop member is advanced into the opening to stop further rotation of the roller in the unrolling direction and prevent further unrolling of the screen from the roller, and said stop member engaging another edge of the opening in the roller for retracting the stop member from the opening when the roller is rotated in the rolling direction to roll the screen upon the roller, said stop member also having wheel means engaging the screen rolled upon the roller to prevent wear during rolling and unrolling of the screen on the roller.

3. In a projection screen for use in exhibiting pictures and having a screen case, a spring actuated roller rotatably mounted in the screen case, a flexible screen secured at one end to the roller and being automatically rolled thereon and having a slat at its other end for unrolling the screen from the roller to picture exhibiting position, the improvement comprising, a latch shoulder stationarily carried by the screen case, a pawl rotatably carried by the roller and movable between advanced and

retracted positions and having a shoulder engaging the latch shoulder when the pawl is in retracted position to prevent rotation of the roller in the rolling direction, said pawl being moved to its advanced position by centrifugal force when the roller is rapidly rotated to allow rotation of the roller in the rolling direction, said roller having an opening therein which is normally covered by the screen rolled thereon and which is exposed only when the screen is unrolled to uncover the opening, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to uncover the opening, said stop member having a stop shoulder engaging one edge of the opening in the roller when the stop member is advanced into the opening to stop further rotation of the roller in the unrolling direction and prevent further unrolling of the screen from the roller, and said stop member engaging another edge of the opening in the roller for retracting the stop member from the opening when the roller is rotated in the rolling direction to roll the screen upon the roller.

4. In a projection screen for use in exhibiting pictures and having a screen case, a spring actuated roller rotatably mounted in the screen case, a flexible screen secured at one end to the roller and being automatically rolled thereon and having a slat at its other end for unrolling the screen from the roller to picture exhibiting position, the improvement comprising, a latch shoulder stationarily carried by the screen case, a pawl rotatably carried by the roller and movable between advanced and retracted positions and having a shoulder engaging the latch shoulder when the pawl is in retracted position to prevent rotation of the roller in the rolling direction, said pawl being moved to its advanced position by centrifugal force when the roller is rapidly rotated to allow rotation of the roller in the rolling direction, said roller having an opening therein which is normally covered by the screen rolled thereon and which is exposed only when the screen is unrolled to uncover the opening, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to uncover the opening, said stop member having a stop shoulder engaging one edge of the opening in the roller when the stop member is advanced into the opening to stop further rotation of the roller in the unrolling direction and prevent further unrolling of the screen from the roller, and said stop member engaging another edge of the opening in the roller for retracting the stop member from the opening when the roller is rotated in the rolling direction to roll the screen upon the roller, the angular relations with respect to the axis of rotation of the roller between the latch shoulder and pawl and the stop shoulder and edge of the spring in the roller being such as to permit rapid rotation of the roller in the rolling direction from a position where the roller is stopped from rotation in the unrolling direction.

5. In a projection screen for use in exhibiting pictures and having a supporting stand, a screen case carried by the supporting stand, a spring actuated roller rotatably mounted in the screen case, a flexible screen secured at one end to the roller and being automatically rolled thereon and having a suspension slat at its other end for unrolling the screen from the roller to picture exhibiting position, and a hook member carried by the stand and spaced from the screen, the improvement comprising, means for releasably securing the suspension slat to the

hook member in picture exhibiting position when the screen is unrolled from the roller and including means connected to the suspension slat for applying a greater tensioning force to the screen than can be applied by the spring actuated roller, said roller having an opening therein which is normally covered by the screen rolled thereon and which is exposed only when the screen is unrolled to uncover the opening, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to uncover the opening, said stop member having a stop shoulder engaging one edge of the opening in the roller when the stop member is advanced into the opening to stop further rotation of the roller in the unrolling direction and prevent further unrolling of the screen from the roller, and said stop member engaging another edge of the opening in the roller for retracting the stop member from the opening when the roller is rotated in the rolling direction to roll the screen upon the roller, and manually controlled means operatively connected between the post and the handle member and hook member for moving the handle member and hook member apart and releasably locking them against movement toward each other when the screen is in picture exhibiting position and rotation of the roller in the unrolling direction is stopped by the stop member for tensioning the resilient means to tension the screen in picture exhibiting position.

6. In a projection screen for use in exhibiting pictures and having a supporting stand, a screen case carried by the supporting stand, a spring actuated roller rotatably mounted in the screen case, a flexible screen secured at one end to the roller and being automatically rolled thereon and having a suspension slat at its other end for unrolling the screen from the roller to picture exhibiting position, and a hook member carried by the stand and spaced from the screen, the improvement comprising, means for releasably securing the suspension slat to the hook member in picture exhibiting position when the screen is unrolled from the roller, said roller having an opening therein which is normally covered by the screen rolled thereon and which is exposed only when the screen is unrolled to uncover the opening, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to uncover the opening, said stop member having a stop shoulder engaging one edge of the opening in the roller when the stop member is advanced into the opening to stop further rotation of the roller in the unrolling direction and prevent further unrolling of the screen from the roller, and said stop member engaging another edge of the opening in the roller for retracting the stop member from the opening when the roller is rotated in the rolling direction to roll the screen upon the roller, and manually controlled means operatively connected between the post and the handle member and hook member for moving the handle member and hook member apart and releasably locking them against movement toward each other when the screen is in picture exhibiting position and rotation of the roller in the unrolling direction is stopped by the stop member for tensioning the resilient means to tension the screen in picture exhibiting position.

tated in the rolling direction to roll the screen upon the roller.

7. In a projection screen for use in exhibiting pictures and having a screen case, a spring actuated roller rotatably mounted in the screen case, a flexible screen secured at one end to the roller and being automatically rolled thereon and having a slat at its other end for unrolling the screen from the roller to picture exhibiting position, the improvement comprising, said roller having an opening therein which is normally covered by the screen rolled thereon and which is exposed only when the screen is unrolled to uncover the opening, a stop member pivotally carried by the screen case in alignment with the opening in the roller, spring means urging the stop member toward the roller against the outermost turn of the screen on the roller and advancing the stop member into the opening in the roller only when the roller is rotated in the unrolling direction to a position where the screen is unrolled to uncover the opening, said stop member having a stop shoulder engaging one edge of the opening in the roller when the stop member is advanced into the opening to stop further rotation of the roller in the unrolling direction and prevent further unrolling of the screen from the roller, and said stop member engaging another edge of the opening in the roller for retracting the stop member from the opening when the roller is rotated in the rolling direction to roll the screen upon the roller.

8. In a projection screen for use in exhibiting pictures and having a screen case, a spring actuated roller rotatably mounted in the screen case, a flexible screen secured at one end to the roller and being automatically rolled thereon and having a slat at its other end for unrolling the screen from the roller to picture exhibiting position, the improvement comprising, said roller having an opening therein which is normally covered by the screen rolled thereon and which is exposed only when the screen is unrolled to uncover the opening, a stop member pivotally carried by the screen case in alignment with the opening in the roller, said stop member being normally urged toward the roller and against the outermost turn of the screen on the roller so as to be advanced into the opening in the roller only when the roller is rotated in the unrolling direction to a position where the screen is unrolled to uncover the opening, the stop member when advanced into the opening engaging one edge of the opening in the roller to arrest further rotation of the roller in the unrolling direction and to prevent further unrolling of the screen from the roller, rewinding of the screen upon the roller when the stop member is advanced into the opening causing another edge of the opening to engage the stop member to retract the stop member from the opening.
